(57) **CLAIM**

The ornamental design for a rear wing for a vehicle, as shown and described.

DESCRIPTION

FIG. 1 is a front right perspective view of a rear wing for a vehicle according to the present invention.

FIG. 2 is a front left perspective view of the rear wing shown in FIG. 1.

FIG. 3 is a rear left perspective view thereof.

FIG. 4 is a rear right perspective view thereof.

FIG. 5 is a front view thereof.

FIG. 6 is a rear view thereof.

FIG. 7 is a raised right side view thereof.

FIG. 8 is a raised left side view thereof.

FIG. 9 is a top view thereof.

FIG. 10 is a bottom view thereof; and,

FIG. 11 is a top view thereof, shown in a position of use. The broken lines and the half-tone showing of a de-emphasized vehicle within the broken lines, illustrate environmental structure that forms no part of the claimed design.
